UNITED STATES PATENT OFFICE.

ISAAC I. FONDA, OF BEVERLY, MASSACHUSETTS.

NON-REFILLABLE BOTTLE.

SPECIFICATION forming part of Letters Patent No. 761,292, dated May 31, 1904.

Application filed November 19, 1903. Serial No. 181,770. (No model.)

To all whom it may concern:

Be it known that I, ISAAC I. FONDA, of Beverly, in the county of Essex and State of Massachusetts, have invented certain new and useful Improvements in Non-Refillable Bottles, of which the following is a specification, reference being had therein to the accompanying drawings.

The invention has reference to improvements in "non-refillable bottles," so called.

The main object of the invention is to so construct a bottle that while the liquid contents may readily be removed from the bottle the refilling of the bottle is rendered impossible or impracticable.

The object of the invention is also to so construct a bottle of this nature provided with a valve and a protector for said valve that the insertion of instruments for removing the valve shall be prevented.

Other objects of the invention will appear from the following description.

The invention consists in such novel features of construction and combination of parts as shall hereinafter be more fully described, and pointed out in the claims.

Figure 1 represents a vertical sectional view of a portion of a bottle and its improved neck, showing the valve and its seat, the valve keeper or protector, and indicating the means whereby the valve-protector is secured in position. Fig. 2 represents a plan view of portions of the same.

Similar numbers of reference designate corresponding parts throughout.

As illustrated in the drawings, in its preferred form this invention comprises a bottle or jar 5 of any desired shape and dimensions and furnished with a neck 6 and a compartment 7 larger than the neck, the outer and inner surfaces of which compartment differ considerably in conformation.

The upper inner surface of the compartment 7 has the inwardly-beveled annular lip 8, which extends to the annular groove 9, which in turn forms the upper limit of the tapering ground-seat 10. Below this seat 10 is the annular enlargement 11, having the shoulder 12 and the more contracted portion 13, which embraces the wall or extension 14,

having the valve-seat 15 and forming an extension to the liquid-delivery channel in the neck 6.

The valve protector or keeper 16 has a conical upper end and a tapering body 17, ground to closely fit the tapering seat 10 of the compartment 7, so that when said body is seated in such compartment the annular groove 9, with the beveled lip 8, will form an entrance to the annular channel formed by the combined grooves 9 and 18. In the lower portion of the body 17 are formed the peripheral grooves 19 19, which extend to the end 20 of said body.

Axially disposed in the body of the valve 65 keeper and protector and open at its upper end to receive a stopper is the tapering socket 21, which extends to the line 22, considerably below the upper ends of the channels 19 19, and through the material of this portion of the body are formed the channels 23 23, located above the line 22 of the socket 21 and connecting said socket with the upper ends of the channels 19.

In the bore or channel of the neck 6 is movably mounted the valve-stem 24, having the ribs 25 25, between which the body of the stem is shaped to permit the flow of liquid. At the upper end of this stem 24 is the inverted conical valve 26, adapted to seat itself in the valve-seat 15 and having the concave upper surface 27, furnished with the rounded projection 28, axially disposed in said concavity. Attention is called in this preferred form of valve to the dimensions of the conical valve 26, the extreme diameter of its upper portion being greater than the distance between the inner walls of the channels 19, whereby a portion of the liquid passing down through said channels will be directed into the concavity 27, and the pressure of such entering liquid will tend to press the valve against its seat. The projection 28 is designed to prevent the intimate and complete contact of the edge portion of the valve with the end 20 of the valve keeper 95 and protector when the bottle is reversed and forms a bearing on which the valve may rock when said projection is brought against this end 20. After the filling of this bottle the valve is first placed in position, as shown, and 100

the valve keeper and protector is then seated in its seat 10, the grooves 9 and 18 thus registering to form an anchorage for fluid cement, which is introduced therein through the entrance formed by the bevel of the lip 8. A cork or other stopper is inserted in the open end of the socket 21 at any convenient point in the operation. When the stopper in socket 21 is removed, the contents of the bottle may be poured out by tipping the bottle in the usual manner, the liquid passing between the ribs 25 25 of the valve-stem and the conical valve being removed from its seat by the pressure of the liquid and by gravity until the projection 28 of the valve contacts with the end 20 of the keeper. In this movement of the valve the undue tipping thereof is prevented by the ribs 25 working against the wall of the channel in the bottle-neck. Upon bringing the bottle to upright position the valve will seat itself in its valve-seat.

Liquid contained in the bottle is free to pass outward through the channels 19 19 and 23 23 and through the socket 21; but if it is sought to introduce liquid into the bottle the liquid passing in through the socket and through the channels 23 23 and 19 will press against the concave surface 27 of the valve and tend to close the same.

30 The insertion of implements for holding the valve open during the refilling of the bottle is prevented by the construction of the valve keeper and protector and by the construction of the compartment 7.

35 The insertion of an implement of a flexible nature through socket 21 into the channels 23 is made difficult by depressing the bottom 22 of said socket below the channels, whereby no means are present for the deflection of the

40 end of the implement into said channels 19, preventing the lateral movement of the implement therethrough to engage the same with the valve, and the end of the implement will be guided by the inclined surface of the

45 seat 10 inward over the top of the valve or following the line of the seat 10 will be in-

tercepted by the wall 14 and will be prevented thereby from entering between the valve and its seat.

While I have herein shown and described 50 a particular form of valve, I do not desire to limit myself thereto, as it is evident that other forms might be utilized without materially departing from the spirit of this invention.

Having thus described my invention, I claim as new and desire to secure by Letters Patent—

1. The combination with a bottle-neck having an inclined wall contracting the inner diameter of the neck toward its lower end, an 60 internal annular enlargement between said inclined wall and the lower end of said neck and an annular wall embracing the outlet from the bottle and extending into said enlargement, of a valve adapted to seat itself in said annular 65 wall, and a valve-keeper seated in the inclined wall of the neck and having side channels which extend toward that portion of the enlargement outside the annular wall.

2. The combination with a bottle-neck having a contracted channel connecting with the bottle, an annular wall extending from said channel to form a valve-seat, a compartment embracing said wall and contracting in diameter above said wall to form an annular shoulder, and a tapering seat above said shoulder, of a valve-keeper adapted to fit said tapering seat and having a tapering stopper-socket, and having longitudinal peripheral channels and having radial channels connecting said stopper-socket with said peripheral channels, and a conical valve 26 having a dished top, furnished with an axial projection, and a stem adapted to work in the contracted channel of the bottle, as and for the purpose described. 85

In testimony whereof I affix my signature in presence of two witnesses.

ISAAC I. FONDA.
